CLAIM

The ornamental design for a hair implant, as shown and described.

DESCRIPTION

FIG. 1 is a top, isometric view of a hair implant showing my new design;

FIG. 2 is a bottom, isometric view of the hair implant of FIG. 1;

FIG. 3 is a front, elevation view of the hair implant of FIG. 1;

FIG. 4 is a rear, elevation view of the hair implant of FIG. 1;

FIG. 5 is a right side elevation view of the hair implant of FIG. 1;

FIG. 6 is a left side elevation view of the hair implant of FIG. 1;

FIG. 7 is a top, plan view of the hair implant of FIG. 1;

FIG. 8 is a bottom plan view of the hair implant of FIG. 1;

FIG. 9 is a top, isometric view of a hair implant showing a second embodiment of my new design;

FIG. 10 is a bottom, isometric view of the hair implant of FIG. 9;

FIG. 11 is a front, elevation view of the hair implant of FIG. 9;

FIG. 12 is a rear, elevation view of the hair implant of FIG. 9;

FIG. 13 is a right side elevation view of the hair implant of FIG. 9;

FIG. 14 is a left side elevation view of the hair implant of FIG. 9;

FIG. 15 is a top, plan view of the hair implant of FIG. 9; and,

FIG. 16 is a bottom plan view of the hair implant of FIG. 9. The features shown in broken lines in the drawing depict portions of the design that form no part of the claimed design.
